GREETING CARD OR THE LIKE

William B. Fitzpatrick, Brookline, Mass.

Application January 26, 1954, Serial No. 28,677

Term of patent 14 years

(Cl. D59—2)

The figure on the drawing is a plan view of a greeting card showing my new design; the reverse side thereof being similarly plain and unornamented.

The dominant feature of the design resides in an ogee-type curve border in which the ogee curve portions are repeated in a distinctive pattern of occurrence so devised that the ogee portions are connected by three-point junctions and two-point junctions reversed in alternating succession.

I claim:

The ornamental design for a greeting card or the like, as shown and described.
